UNITED STATES PATENT OFFICE.

LA FAYETTE WILDERMUTH, OF COLUMBUS, OHIO.

GRASS-RECEPTACLE FOR LAWN-MOWERS.

SPECIFICATION forming part of Letters Patent No. 607,899, dated July 26, 1898.

Application filed May 15, 1897. Serial No. 636,666. (No model.)

To all whom it may concern:

Be it known that I, LA FAYETTE WILDERMUTH, a citizen of the United States, residing at Columbus, in the county of Franklin and 5 State of Ohio, have invented a new and useful Grass-Receiptacle for Lawn-Mowers, of which the following is a specification.

My invention relates to a grass receptacle and carrier for lawn-mowers, and has for its 10 object to simplify and improve the construction of devices applicable to ordinary forms of lawn-mowers for receiving cut grass, the construction of the frame being such as to allow upward yielding of its bottom at the rear 15 end without permitting displacement of the bottom at its front end.

A further object of the invention is to provide such a connection between the looped upper and lower frames of the receptacle and 20 the spring whereby said frames are contracted at their front ends to maintain the attaching devices in their normal positions, so as to insure strength and solidity without interfering with the vertical movement of the rear 25 end of the lower frame.

Further objects and advantages of this invention will appear in the following description, and the novel features thereof will be particularly pointed out in the appended 30 claim.

In the drawings, Figure 1 is a perspective view of a receptacle constructed in accordance with my invention applied in the operative position to a lawn-mower. Fig. 2 is a detail 35 view in perspective of one end of the frame with the webbing or bagging omitted. Fig. 3 is a detail view of the spring-actuated loops detached. Fig. 4 is a detail view in perspective of the joint between the members of the 40 receptacle-frame, showing the same from the inner side. Fig. 5 is a transverse sectional view of the loops and actuating-spring.

Similar numerals of reference indicate corresponding parts in all the figures of the drawings.

The frame of the receptacle comprises an upper member 1, forming the side and rear edges of the top of the receptacle and having depending front arms 2 and a lower member 50 3, forming the side and rear edges of the bottom and connected at its extremities to the depending arms 2 of the upper member.

Each frame member is preferably constructed of a single blank of wire or rod, and the connection therebetween, which is in the plane of 55 the lower member, is pivotal or hinged to allow a vertical swinging movement of the rear portion thereof, whereby the depression of the lawn-mower handle 4 sufficiently to bring the lower frame member of the receptacle into 60 contact with the ground will result in the displacement of no other portion of the device than the rear end of the frame member 3, which will receive an upward swinging movement. This pivotal or hinged connection is 65 formed by coiling the depending arms 2 of the upper frame member to provide eyes 5, with which are engaged terminal eyes 6 on the side arms of the bottom frame member.

The eyes 5 of the upper frame member are 70 disposed at intermediate points of the wire or rod forming said member, and beyond said eyes the member is extended forward in an approximately - horizontal direction to provide attaching-arms 7, having inturned terminals 75 or trunnions 8 for engagement with openings, such as slots 9, in the frame of the lawn-mower. It is obvious that the elasticity of the receptacle-frame operates, when it is properly proportioned to suit the frame of the 80 lawn-mower, to maintain the terminals or trunnions 8 in the openings provided for their reception; but in order to insure the positive engagement, and hence the maintenance of the device in operative position, I employ 85 frame - contracting devices connecting the sides of the receptacle-frame in a plane contiguous to that of the loose connection between the upper and lower frame members, and hence contiguous to the plane of the attaching-arms 7. In the construction illustrated these contracting devices consist of spring-actuated loops 10, engaged at their looped extremities, respectively, with the frame members at transversely - opposite 90 points, as with the eyes 6, and connected at their opposite extremities to an actuating-spring 11, said spring being disposed mainly between the hooked extremities 12 of the loops, whereby the extension of the connection between the transversely-opposite points of the receptacle-frame causes the contraction of the actuating-spring. Furthermore, the arrangement of the spring upon the por- 100

tions of the actuating-loops between the terminal hooks 12 thereof prevents the deflection of said spring. The intermediate overlapping portions of the loops form a core or stiffener 5 which maintains the coils of the spring in alinement.

From the above description it will be seen that in applying the receptacle embodying my invention to the frame of a lawn-mower

- 10 it is simply necessary to expand the receptacle-frame laterally in opposition to the tension of the spring 11 to separate the attaching-arms 7 sufficiently to allow the terminals or trunnions 8 to engage suitable openings 15 in the lawn-mower frame, after which the release of the receptacle-frame and the resulting expansion of the spring 11 will cause the transverse contraction of the receptacle-frame and the efficient engagement of the terminals 20 or trunnions 8 with the lawn-mower frame. The rear end of the upper frame member is preferably supported by means engaged with the handle of the lawn-mower, as by a link 13, provided with a terminal hook 14, which 25 is seated upon the said handle.

In order to prevent the transverse contraction of the receptacle-frame from disengaging the terminal hooks 12 of the loops 10 from the coils of the spring 11, I preferably engage 30 said hooks with the springs at intermediate points of the latter, thus leaving one or more terminal coils 11^a of said spring beyond or outside of the hooks 12.

- 35 An important feature of the construction of the frame of my improved grass-receptacle resides in the connection of the frame members, whereby while pivotal movement of the lower member is allowed no vertical displacement of the front end of said member 40 with relation to the upper member can occur. The interlocking eyes of the two

members, whereby the same are connected, prevents vertical displacement of the lower member at its front end.

Various changes in the form, proportion, 45 and the minor details of construction may be resorted to without departing from the spirit or sacrificing any of the advantages of this invention.

Having described my invention, what I 50 claim is—

A grass-receptacle for lawn-mowers having a wire frame comprising upper and lower looped members having forwardly-extending arms intersecting in the plane of the lower 55 member, and provided with interlocking eyes 5 and 6, the arms of the upper member being extended beyond said interlocking eyes to form inturned engaging studs, and yielding means connecting the sides of the 60 frame at the point of intersection of said loop-arms, said means consisting of oppositely-extending loops 10 having their closed extremities engaged with the eyes 5 of the upper frame member, and having their open 65 ends provided with outwardly-turned hooks 12, and an expansion-spring coiled upon the overlapping portions of said loops and engaged at intermediate points by the hooks, which extend between the coils of the spring 70 at points set in from the extremities of the latter, to prevent disengagement of the hooks by the lateral contraction of the frame, substantially as specified.

In testimony that I claim the foregoing as 75 my own I have hereto affixed my signature in the presence of two witnesses.

LA FAYETTE WILDERMUTH.
